A. CAMPBELL.
CAR FLOOR DOOR OPERATING MECHANISM.
APPLICATION FILED APR. 9, 1906.

UNITED STATES PATENT OFFICE.

ARGYLE CAMPBELL, OF CHICAGO, ILLINOIS.

CAR-FLOOR-DOOR-OPERATING MECHANISM.

No. 825,581.

Specification of Letters Patent.

Patented July 10, 1906.

Application filed April 9, 1906. Serial No. 310,815.

To all whom it may concern:

Be it known that I, ARGYLE CAMPBELL, a citizen of the United States, residing at Chicago, in the county of Cook and State of Illinois, have invented a certain new and useful Improvement in Car-Floor-Door-Operating Mechanism, of which the following is a specification.

My invention relates to car-floor-door-operating mechanism, and is a modification of the invention shown, described, and broadly claimed in my prior application, Serial No. 308,048, filed March 26, 1906.

The object of my invention is to provide a novel form of mechanism by which a door may be hinged at two opposite sides upon two independent operating mechanisms and operated from either side about the hinge on the opposite operating mechanism so as to tilt the door in either of two desired opposite directions.

My invention consists in a novel form of mechanism capable of accomplishing these objects which can be easily and cheaply made and installed, which is efficient in operation, and is not readily liable to get out of order.

More in detail, my invention consists in the use of two parallel shafts at the edges of and preferably clear of the swinging edge of each door to be operated, there being adjacent to each door on each crank-shaft a pair of crank-arms connected with a common crank-pin, which slides backward and forward in a slot in a block upon the under side of the door, preferably extending outside the edge of the door, so that if either crank-shaft is rotated while the other shaft remains at rest the door is tilted by the moving crank-shaft about the crank-pin of the opposite door as a hinge. By this construction when shafts extending longitudinally of the car are used I am able to dump load, as desired, at either the center of the track or at the side of the track.

My invention further consists in details of construction which will be hereinafter more fully described and claimed.

Figure 1 is a longitudinal side view, partially in section, of a car having the device of my invention applied thereto. Fig. 2 is a transverse sectional view of one-half of a car, showing the details of my invention when the floor-door is closed. Fig. 3 is a similar view to Fig. 2, showing in full lines the position of the door when the outside operating mechan-

ism has been manipulated to tilt the door to 55 discharge load at the side of the car and showing in dotted lines the position which the door assumes when the inside operating mechanism has been manipulated to tilt the door to discharge load at the center of the car 60 or track. Fig. 4 is a detail of a supplemental locking mechanism.

In the drawings I have shown my device as applied to a car of the hopper type; but this feature is not essential to my invention, as the 65 mechanism may be applied to any other type of car with load-carrying floor-doors. In the particular car here shown the load-carrying hopper 10 is supported upon an underframe consisting of a central girder 11, with a plurality of cross bearers or bolsters 12 extending therefrom crosswise of the car. The particular construction of this underframe is no part of my invention. In this hopper at one side of the central girder, as shown in Figs. 2 70 and 3, and between a pair of cross-bearers 12 is a rectangular opening defined by the lines 15, 16, 17, and 18, through which load is discharged out of the hopper. This load-discharging opening is normally closed by a 75 load-carrying floor-door 20, unsupported adjacent to the floor of the car except by two operating mechanisms, which will now be described.

This door just described is only one of several on the same side of the central girder operated by a single set of shafts, and in a complete car another set of shafts and doors are placed along the car on the opposite side of the central girder from the door here shown. 80 85 90

Adjacent to the longitudinal center girder of the car I secure to the cross members of the underframe by any suitable hangers, such as 22, a longitudinal shaft 23, having between the pair of cross-bearers adjacent to 95 the load-discharging opening above described two crank-arms 25, connected by a common crank-pin 26.

On the under side of the door 20, adjacent to each opposite end of the crank-pin 26, is secured at right angles to said crank-pin a block or blocks, preferably castings 28, having cut in them below the level of the door elongated slots 30, in which the crank-pin 26 is adapted to travel backward and forward. 100 105 On the crank-pin 26, adjacent to these castings 28, are rollers 31, adapted to travel backward and forward on tracks 33, which are

flanges of the castings 28, heretofore referred to. The castings 28 are made of such a length and the slots 30 are of such length that when the shaft 23 is rotated from the position of Fig. 2 to the dotted-line position of Fig. 3 the crank-shaft 26 will move in said slot sufficiently to tilt the door from the full-line position of Fig. 2 to the dotted-line position of Fig. 3. As the length of the crank-pin 26 is less than the length of the floor-door 20, the door cannot swing down between the crank-arms, and I therefore in order to obtain the opening desired, as described, extend the blocks 28 outside the inner edge of the floor-door, as shown.

Upon hangers 40 or other suitable supports upon the outer ends of the cross-bearers of the underframe I journal another shaft 43, parallel to the shaft 23, heretofore described, the same having crank-arms 45 and a common connecting crank-pin 46, exactly duplicating the parts 25 and 26, heretofore described. On the outer edge of the car-door, adjacent the crank-pin 46, are castings 48, having slots 50 containing the crank-pin 46, exactly duplicating the castings 28 with the slot 30, heretofore described.

On the crank-pin 46 are rollers 51, traveling upon flanged tracks 53, which are flanges of the casting 48 and identical with the tracks 33, heretofore described.

On the outer end of each shaft 23 and 43 is a ratchet-wheel 55, locked by a pawl 46, the one on shaft 23 being a right-handed one adapted to prevent clockwise motion of the shaft 23 when viewed as shown in Figs. 2 and 3, while the pawl on shaft 43 is a left-handed one or adapted to prevent counter-clockwise motion of the shaft 43 when viewed as shown in Figs. 2 and 3.

On each shaft 23 and 43 there is a sprocket-wheel 60 connected by a chain 61 to a shaft 62 and hand-wheel 63, corresponding to that shown in Fig. 5 of my said prior application, each of said mechanisms being designed to operate the particular shaft to which it is attached. These operating mechanisms do not form any part of my invention, and any other operating mechanism may be substituted without departing from my invention.

All of the parts heretofore described are so proportioned and arranged that when all the parts are in normal position they appear as seen in Fig. 2, the shafts being held by their respective ratchet-wheels and pawls heretofore described, thereby holding the door in normal closed position.

When now the operator desires to dump a load which is in the hopper 10, resting upon the floor-door 20 at the center of the car or track, he leaves shaft 43 in stationary position and releasing the pawl 56, controlling shaft 23, takes hold of the hand-wheel-controlling shaft 23 and rotates that shaft from the position of Fig. 2 to the dotted-line posi-

tion of Fig. 3, in which position the load slides off from the door toward the center of the track. When the load has thus been discharged, the operator takes hold of the hand-wheel-operating shaft 23 and rotates it in the opposite direction, thereby returning the parts from the dotted-line position of Fig. 3 to the full-line position of Fig. 2, the pawl 56 clicking over the ratchet-wheel 55 on shaft 23, thereby protecting the operator against backward motion of the shaft during the raising operation, and finally locking the shaft in the position of Fig. 2.

When now the operator desires to dump load which is upon the door 20 at the side of the track, he releases the pawl 56, controlling the shaft 43, leaving shaft 23 in locked position, and taking hold of the hand-wheel-controlling shaft 43, rotates it from the position of Fig. 2 to the full-line position of Fig. 3, in which position the load upon the door slides off at the side of the car-track. When this has been accomplished, the operator takes hold of the hand-wheel controlling the shaft, rotates it in the opposite direction from the full-line position of Fig. 3 back to the dotted-line position of Fig. 2, the pawl 56, controlling shaft 43, clicking over the ratchet-wheel on that shaft, and finally locking the shaft 43 in normal position.

It will be noted that each shaft 23 and 43 is located entirely clear of the swinging edge of the door to which it is adjacent, so that the door may swing entirely past its center to the lower positions named. In order to permit of each shaft operating the door, as described, it is necessary that the castings or blocks 28 and 48 extend some little distance beyond the edge of the door, as heretofore described, and it is therefore necessary that the slots 30 and 50 extend into said extended portions of said castings. This construction gives the crank-shaft and crank-arms which are being used to operate the particular edge of the door a very powerful leverage upon the door to close it and enable extra-wide doors to be used without interfering with the operating mechanism.

This mechanism can be used as operating means for a door hinged only on one side of the door, and claim 7 is intended to cover such a construction.

In Fig. 4 I provide additional locking means when the door does not close quite tight by rounding out the ends of the slots 30 or 50 in the curved line 68.

Having thus described my invention, what I claim as new, and desire to secure by Letters Patent, is—

1. In a car, in combination with a frame, a load-retaining car-body, a load-carrying-floor door normally closing a load-discharging opening in the body, two independent shafts adjacent to opposite sides of the door, a crank-arm and its crank-pin on each shaft, 125

- each crank-pin being adapted to move backward and forward upon the under side of the door, mechanism for holding the crank-pin in contact with the door throughout said movement, mechanism for normally locking each shaft in stationary position, and mechanism for independently rotating either shaft about the stationary crank-pin of the opposite shaft.
5. In a car in combination with a frame, a load-retaining car-body, a load-carrying-floor door normally closing a load-discharging opening in the body, two independent shafts adjacent to opposite sides of the door, each 15 shaft having a crank-arm carrying a crank-pin adapted to move backward and forward upon the under side of the door, a block upon the under side of the door adjacent to the path of travel of each crank-pin along the door, there being an elongated slot in each 20 block adapted to have its crank-pin travel therein, as described, mechanism for normally locking each shaft in stationary position, and mechanism for independently rotating either shaft about the stationary 25 crank-pin of the opposite shaft.
3. In a car in combination with a frame, a load-retaining car-body, a load-carrying-floor door normally closing a load-discharging 30 opening in the body, two independent shafts adjacent to opposite sides of the door, each shaft having a crank-arm carrying a crank-pin, adapted to move backward and forward upon the under side of the door, a block for 35 each crank-pin secured upon the under side of the door extending beyond the edge of the door, there being an elongated slot in each block extending into the extension portion thereof, in which the crank-pin is adapted to 40 travel backward and forward, mechanism for normally locking each shaft in stationary position, and mechanism for independently rotating either shaft about the stationary 45 crank-pin of the opposite shaft.
4. In a car, in combination with an under-frame consisting of a central girder and cross members, a load-carrying-floor door between a pair of cross members at one side of the central girder, occupying less space than the distance between the central girder and the side 50 of the car, a pair of longitudinal shafts mounted upon the cross members of the underframe at each side of the door, one shaft near the central girder and one shaft near 55 the side of the car, a pair of crank-pins upon each shaft adjacent to one edge of the door, a common crank-pin connecting said crank-arms adapted to be moved backward and forward on the under side of the door, means 60 for holding said crank-pin in engagement with the under side of the door in all positions during the operation of the shaft, means for independently locking both shafts, and independent mechanism for rotating either 65 shaft to tilt the door about the locked crank-

pin of the other shaft to discharge load from the edge of the door adjacent to the operated shaft.

5. In a car in combination with an under-frame consisting of a central girder and cross members, a load-carrying-floor door between a pair of cross members at one side of the central girder occupying less space than the distance between the central girder and the side of the car, a pair of longitudinal shafts mounted 70 upon the cross members of the under-frame at each side of the door, one shaft near the central girder and one shaft near the side of the car, a pair of crank-pins upon each shaft adjacent to one edge of the door, a common crank-pin connecting said crank-arms adapted to be moved backward and forward on the under side of the door, a block upon the under side of the door adjacent to each crank-pin having an elongated 75 slot in which said crank-pin is adapted to travel backward and forward as described, means for independently locking both shafts, and independent mechanism for rotating either shaft to tilt the door about the locked 80 crank-pin of the other shaft to discharge load from the edge of the door adjacent to the operating-shaft.

6. In a car in combination with an under-frame consisting of a central girder and cross members, a load-carrying-floor door between a pair of cross members at one side of the central girder occupying less space than the distance between the central girder and the side of the car, a pair of longitudinal 90 shafts mounted upon the cross members of the underframe at each side of the door, one shaft near the central girder and one shaft near the side of the car, a pair of crank-arms upon each shaft adjacent to the one edge of 95 the door, a common crank-pin connecting said crank-arms adapted to be moved backward and forward on the under side of the door, a block upon the under side of each door extending outside of the edge thereof 100 adjacent to each crank-pin, there being an elongated slot in each block extending into the extension portion thereof in which each crank-pin is adapted to move backward and forward as described, means for independently locking both shafts, and independent mechanism for rotating either shaft to tilt the door about the locked crank-pin of the other shaft to discharge load from the edge 105 of the door adjacent to the operated shaft. 110

7. In a car, in combination with a frame, a load-retaining car-body, a load-carrying-floor door normally closing a load-discharging opening in the body, a pivotal mounting for said door at one of its edges, a block upon the opposite edge extending outside said edge, an elongated slot in said block extending into said extension portion of the block, a shaft adjacent to the said block and clear of the swinging edge of the door, a crank-arm 125 130

on said shaft, a crank-pin on said crank-arm entering and adapted to be moved backward and forward in said slot, as described.

8. In a car in combination with a frame and hinged door adapted to retain a load, a shaft pivotally mounted adjacent to a swinging free edge of the door, a crank-arm and crank-pin on said shaft, the crank-pin extending into an elongated slot on the under side of the door, and an enlarged portion 68 at the end of the slot where the crank-pin

normally rests in stationary position adapted to assist in locking the crank-pin in normal position, as described.

In witness whereof I have hereunto subscribed my name in the presence of two witnesses. 15
